UNITED STATES PATENT OFFICE.

GEORGE H. MAHAN, OF CHICAGO, ILLINOIS, ASSIGNOR TO GEORGE O. HOPE AND
GEORGE H. MAHAN, COPARTNERS DOING BUSINESS AS ATLAS OIL BURNER COM-
PANY, OF CHICAGO, ILLINOIS.

OIL BURNER.

Application filed August 7, 1922. Serial No. 579,983.

To all whom it may concern:

Be it known that I, GEORGE H. MAHAN, a citizen of the United States, residing at Chicago, in the county of Cook and State of Illinois, have invented a certain new and useful Improvement in Oil Burners, of which the following is a full, clear, concise, and exact description, reference being had to the accompanying drawings, forming a part of this specification.

This invention relates to improvements in oil burners and particularly to oil burners in which kerosene, distillate or gas oil may be used.

I am aware that it is old in the art to provide oil burners comprising a bowl and an arch extending diametrically across the same having air intake openings at the front and back of the bowl and a fuel supply opening at the center of the arch. This construction is subject to the disadvantage of having the arch obstruct the rear of the bowl and thus preventing the flames from being properly distributed over the rear of the interior of the fire box and causing the spreading of the flames laterally of the firebox. The rear wall of the furnace or boiler is thus permitted to remain cool and the corresponding amount of heating surface not efficiently utilized. The old construction interferes with the air freely entering the rear opening in the arch on account of the draft created through the forward part of the arch.

In my improved device, I have overcome these difficulties by extending the arch from the center of the bowl to the forward side only of the same, thereby getting the benefit of all of the available draft and preventing the obstruction of the flames at the rear of the bowl.

The object of my invention is to provide an oil burner which is simple in construction and efficient in operation, and wherein an ample supply of air is provided to insure complete combustion of the fuel. A further object of the invention is to so arrange the air intake of the burner that the full supply of air will be taken directly from the front of the furnace, closely adjacent to the ash-pit doors and directly delivered to the center of the burner at the point where the oil is fed.

It is a further object of my invention to so construct the arch through which the air

is conveyed to the burner that the greater part, and especially the entire rear portion of the burner bowl will have no obstruction above the same to interfere with the free play of the flames upon the fire pot walls.

Other objects of the invention will more clearly appear from the description and claims hereinafter following.

In the drawings, Fig. 1 is a plan view of the improved burner showing the air ducts within the arch in dotted lines. Fig. 2 is a vertical section on line 2—2 of Fig. 1 showing by dotted lines, the front wall of a conventional furnace. Fig. 3 is a vertical section through the arch member taken substantially on the line 3—3 of Fig. 1. Fig. 4 is a front elevation of the burner and Fig. 5 is a sectional view similar to that shown in Fig. 2, of a modified construction of the burner.

In said drawings, 10 indicates the bowl of the burner, 11 the arch and 12 the supporting plate on which the bowl and arch are held. The bowl 10 is of dish-shape, having a bottom and side wall 13, of generally curved concavo-convex form, terminating in a vertically extending wall 14 along the forward side. The bottom of the wall 13 has a central conical raised portion 15, centrally perforated at 16 to receive an oil feeding pipe 17, for conveying the oil to the burner. The bowl 10 is provided with a circular downwardly extending flange at its bottom, indicated by 18, which acts as an attaching means for holding the bowl in proper position on the supporting plate 12. The centrally located conical projection 15 forms an oil distributing device whereby the oil fed through the vertically extending pipe 17 is caused to be properly distributed in a film to provide for complete combustion of the same. The cone 15 has a stepped outer surface 19, the steps of which are provided with grooves 20, thereby forming troughs to check or retard the flow of the oil down the face of the cone. The bowl 10 is also provided with means for preventing the overfilling of the same, should the flame be extinguished accidentally. This means comprises a drain pipe 21 connected with the bowl 10 at about half its height and communicating with the opening 22.

The arch 11 comprises two vertically extending tubular portions 23 communicating

with the upwardly and inwardly curved tubular portions 24, merging into a single downwardly curved tubular portion 25 which terminates in a vertical tubular portion 26 having its open end located centrally above the bowl 10 and in axial alignment with the oil pipe 17. The tubular portions 23 are provided at their lower ends each with a downwardly extending lug 27 and a horizontally extending lug 28. The lugs 27 and 28 provide suitable means for attaching the arch to the supporting plate 12.

The supporting plate 12 is provided with a central recess 29 which snugly receives the flange 18 on the bottom of the bowl 10 to hold the same in proper position. The supporting plate 12 is also provided at the forward side with two recesses 30, of the same general outline as the lower ends of the tubular members 23. These openings are of such a size as to provide an abutment 31 for the lower ends of the tubular portions 23. At the forward end of the recesses 30, are provided U-shaped strap portions 32 adapted to receive the lugs 28 of the tubes 23. It will be noted that the lugs 27 and 28 co-acting, respectively, with the inner walls of the recesses 30 and the U-shaped strap portions 32, will hold the arch member in properly supported assembled relation on the plate 12.

As shown in Fig. 2, the burner is so arranged within the furnace, the front wall 35 of which is indicated by dotted lines in said figure, that the tubular portions 23 will be located near the front of the furnace. In Fig. 2, the fire box doors of the furnace are designated by 33 and the ashpit doors are indicated by 34, and 35 indicates a supporting flange which provides means for holding the usual grates of the furnace in proper position. In placing the burner within the fire box of the boiler, the plate 12 is supported by the flange 35, which ordinarily supports the grates.

The modification shown in Fig. 5 differs from the construction previously described in that the supporting plate 12 is replaced by a cylindrical support 121. The bowl 110 is of substantially the same construction as the bowl 10 with the exception that an abutment is provided at the upper end of the wall 114 to support the lower end of the tubular members 123. The tubular members 123 are provided with lugs 127 and 128, which co-act with the wall 114 and a U-shaped strap 132 on the bowl 110 and the cylindrical support 121, respectively, thereby holding the arch 111 in assembled relation to the support 121. The cone 115 is of similar construction to the cone shown in the preferred form, differing only in that fewer steps are provided. The feed pipe 117 connects with the opening at the upper

end of the cone 115, similarly to the construction shown in Fig. 2, and an oil overflow drain pipe 121, communicating with an opening 122, is also provided to prevent overflowing of the bowl.

In using my burner, oil is fed through the pipe 17 by gravity, although other means may be provided for feeding the oil. In connection with the oil feed line, the usual thermostatically controlled needle valve is provided, to properly control the flow of the oil according to the temperature desired. The oil passing through the pipe 17 flows over the top of the cone 15 and down the stepped portions 19, a small quantity of the oil being retained in each of the troughs 20, during the downward flow of the same, to cause a proper distribution of the oil circumferentially of the cone substantially as a film. The air is admitted through the openings in the lower ends of the tubular portions 23 of the arch 11, passing along the same to the terminal end of the arch, comprising the tubular portion 26 located axially with reference to the oil feed pipe 17. By this means a strong draft of air is induced directly downwardly over the cone and is properly spread by the same to insure complete combustion of the oil being distributed over the outer face of the cone. In this connection it will be noted that a very strong draft is provided at the outlet end of the arch, due to the large area of the combined intake openings at the lower ends of the tubular members 23 of the arch. It will also be seen that as the inlet openings of the arch are located immediately adjacent the ash pit doors 34, there will be no obstruction to the free entrance of the air. The concave construction of the bottom wall of the bowl 10 provides for a proper deflection of the flames upwardly as the draft is directed downwardly along the conical walls of the projection 15 and upwardly along the curved walls of the bowl.

As heretofore indicated, my improved burner is adapted to be used in furnaces, boilers, etc. particularly those used for domestic purposes. As is well known, that portion of the fire pot wall on the front side of the heater adjacent the feed and ash pit doors, does not obtain the same high temperature as do other portions of the fire box wall, and especially the rear portion which, in most instances, is the most efficient portion of the fire box in heating either the circulating air or water, whichever it may be. With my arrangement, I bring the intake ends of the arches or air ducts as closely adjacent the front portion of the fire pot walls, as possible, so that there is in effect, no appreciable decrease in the effective radiation obtained from such front portions of the fire pot wall, and I leave the major portion of the bowl, including

the back portion thereof, free and unobstructed so that the flames of combustion may be deflected against the greater part of the fire pot walls and, in particular, 5 against those portions which are the most efficient in radiating heat. In actual practice, each intake opening of the arches or air ducts will be made of an area approximately equal to the area of the discharged 10 end of the merged arches so as to insure a strong draft downwardly over the surface of the stepped cone.

In the normal operation of the burner, the oil flowing over the cone 15 will be consumed before it reaches the bottom of the cone, but should the burner for any reason be accidentally extinguished, the oil will be prevented from overflowing the bowl by passing out through the opening 22 upon 20 reaching the level of the same and passing off through the drain pipe 21. In the preferred construction, the drain pipe 21 is connected to a proper safety valve mechanism for cutting off the supply of oil to the feed 25 pipe 17. It will thus be seen that the supply of oil may be automatically cut off by this means when the burner is accidentally extinguished.

My burner is capable of successfully burning 30 kerosene which has a specific gravity of approximately 47, distillate having a specific gravity of approximately 38 and gas oil having a specific gravity of about 36.

All the parts of my burner are preferably 35 constructed of gray cast iron.

I have herein shown and described what I now consider the preferred manner of carrying out my invention, but the same is merely illustrative and I contemplate all 40 changes and modifications that come within the scope of the claims appended hereto.

I claim:

1. As an article of manufacture, an oil 45 burner adapted to be used in furnaces and other heaters having the usual door openings in the front thereof, said oil burner comprising, a bowl with a concave upper face adapted

ed to be placed approximately in the center of the fire pot of the heater, said bowl having an upwardly projecting cone-shaped fuel 50 distributor in the center thereof; means for supplying and delivering fuel at the top of said cone-shaped distributor to permit the fuel to flow downwardly over the distributor; and means for supplying air to combine 55 with the fuel, said means including a member having an air delivery opening disposed over the top of the cone distributing means and intake openings disposed at the front of the bowl and adapted to be positioned immediately adjacent the front of the heater, the combined area of said openings being greater than the area of said delivery opening, the top of the bowl being unobstructed throughout its major portion, including the 60 back portion thereof.

2. In a liquid fuel burning apparatus, the combination with a receptacle adapted to be disposed within the fire box; of means for feeding liquid fuel to the center of the receptacle; and means for conveying air to the point where the fuel is delivered, comprising an arch member having two branches merging into a single terminal portion located above the receptacle and in alinement 75 with the point where the fuel is delivered, each of said branches extending toward the front of the receptacle and terminating beyond the outer edge of the same and adapted to be positioned immediately adjacent the 80 fire box and ash pit doors of the furnace, said branches each being provided with an air passage extending from end to end and merging into a single outlet at said terminal of the arch, the combined areas of the 85 intake openings of said passages being greater than the area of the outlet opening.

In witness that I claim the foregoing I have hereunto subscribed my name this 28 day of July, 1922.

GEORGE H. MAHAN.
